UNITED STATES PATENT OFFICE.

WILLIAM S. G. BAKER, OF BALTIMORE, MARYLAND.

CAR-TRUCK.

SPECIFICATION forming part of Letters Patent No. 399,466, dated March 12, 1889.

Application filed June 7, 1888. Serial No. 276,358. (No model.)

To all whom it may concern:

Be it known that I, WILLIAM S. G. BAKER, a citizen of the United States, residing at Baltimore, in the State of Maryland, have invented certain new and useful Improvements 5 in Car-Trucks, of which the following is a specification.

My invention relates to that class of car-trucks in which the car-body is supported on 10 springs mounted in frames or carriages supported on the axle-boxes.

The object of the first part of my invention is to so arrange the springs and their frames or carriages, and so connect them to the car-body and to the axle-boxes that the car-wheels and their axle-boxes may be removed without 15 removing the springs or unnecessarily disarranging the other parts of the gear.

To this end my invention consists in providing supports or fastenings independent of 20 the spring frames or carriages to sustain the springs, spring-seats, and like parts when the wheels, axles, and spring-carriages are removed. In this connection my invention also 25 consists in an improved way of constructing and organizing the springs, spring-posts, spring-carriages, guide-posts, and brace-rods, as will be hereinafter described and claimed.

The object of the next part of my invention 30 is to provide improved means for supporting the grip-bars and life-guards of the cars of cable railroads.

To this end my invention consists in providing the axle-boxes with hangers of an improved construction, having seats in which the grip-bars are mounted, and in which they are free to rock. In this connection my invention also consists in an improved way of 35 attaching the hangers to the axle-boxes, an improved form of grip-bar, an improved way 40 of forming the seat for the grip-bar, and in improved devices for limiting the movement of the grip-bar in its seat.

In the accompanying drawings, Figure 1 is 45 a side elevation of a car-wheel with the truck-gear therefor. Fig. 2 is an end view with the wheel and grip-bar in section. Fig. 3 is a side view of the lower part of the car-wheel and its gear, showing parts of the gear broken away. Fig. 4 is an end view of an axle-box 50 with a car-wheel in section, showing also the grip-bar in section and parts of the gear

broken away. Fig. 5 is a bottom view of the grip-bar and its hanger. Fig. 6 is an elevation of a modified form of gear with my improved devices for supporting the springs in 55 this kind of gear. Fig. 7 is a detailed view of a section of the braces, and Fig. 8 is a detailed view of the improved devices for supporting the springs. 60

The spring-carriage A is supported on the axle-box B by means of a link, B', which rests on the top of the box and passes through recesses a in the carriage adjacent to the box, and then under the bottom of the carriage. 65 The carriage A has laterally-projecting arms or brackets A', on which rest guide-blocks C, which are held firmly in place on the carriage by means of lugs or dowels c, which fit in corresponding recesses, c', in the upper face of the 70 brackets. If preferred, however, the guide-blocks may be formed in one piece with the carriage. The guide-blocks also are provided with recesses c'', through which the link B' extends. 75

On laterally-projecting arms C' of the guide-blocks rest gum cushions D, carrying plates D', in the upper faces of which the lower ends of the supporting-springs E are seated. The upper ends of the springs extend into 80 recesses or seats E' in a cross-bar, F. The upper face of the bar F at each end is provided with seats f, in which rest the gum cushions G, which also extend into seats g in the car-sill H. The spring-posts I are secured 85 at their upper ends to the car-sill, and extend through the cross-bar F, the springs E, gum cushions D, plate D', guide-blocks C, and carriage A, and are screw-threaded at i to receive nuts I', between which and the 90 bottom of the carriage are interposed gum washers I''. The openings i' in the carriage are larger than the nuts I' and the gum washers I'', so that the carriage may be withdrawn over the washers and nuts. The posts I are 95 preferably shouldered at i', and the reduced ends pass through section J'' of the brace-rods J. Nuts J', working on the screw-threaded ends of the posts, secure the rod-section J'' in position on the posts. The form of the brace-rod section is shown in Fig. 7. 100

The guide-posts K are secured to the car-sill H, and extend through perforations K' in the guide-blocks and in the spring-car-

riage. The lower ends of the posts K are preferably shouldered at k, and the ends extend through openings j in the brace-rod section J^x.

5 Nuts L, working on the screw-threaded ends of the posts K, secure them to the brace-rod section J^x. The brace-rods may be connected to the car-body in the usual way. I preferably, however, secure the section J^x to the main portion of each brace-rod by a sleeve-nut, J³, so that this section of the brace-rod may be removed without disarranging the other parts of the braces. The gear thus organized firmly supports the car-body on the axle-boxes. The boxes are free to move vertically with the spring-carriages, being guided truly by the posts K, and the boxes may have a lateral movement within the links B' in the usual way. By removing the nuts J' and L and taking away the sections J^x of the brace-rods, the carriages may be removed from the posts I and K, and taken off with the wheels, axle, and axle-boxes, without disturbing the springs, gum cushions, or cross-bars, and, 5 when the guide-blocks are made separately, as shown in the drawings, they also are not disturbed.

Instead of placing the nuts I' on the posts I they may be placed on the posts K, as shown in Fig. 3, and perform the same function, or they may be used in both places, the openings in the carriage being large enough to permit the carriage to be withdrawn over the nuts without removing them. When the 5 nuts I' are placed on the posts K, as shown in Fig. 3, gum washers I² are arranged on the posts I between the brace-rod J and the bottom of the carriage.

In Fig. 6 a different form of car-gear is shown, in which the link B' is dispensed with and the carriage secured directly to the box or formed therewith. The carriage has brackets A', on which rest plates A², provided with seats for the gum cushions D. Plates D', resting on the gum cushions, have seats for the springs E. Nuts I' are secured onto the posts below the carriage, and between the bottom of the carriage and the nuts are interposed washers I². The openings in the carriage above the washers and nuts I² and I' are large enough to permit of the carriage being withdrawn over them. The construction is similar to that described in connection with Figs. 1, 2, and 3 of the drawings, and the braces are connected in a similar way. The guide-blocks C are in this instance formed on the brace-rod section J^x.

In cars for cable railways the grip devices are usually supported on frames located below the boxes. I propose to support the grip-bars M on each side in a hanger, N, secured to lugs or ears O' in a saddle-piece, O, which extends over the top of the axle-box on which it rests. The saddle-piece O is preferably made narrow at the top, where it rests on the box, and widens as it extends downwardly by

the side of the box. The ears or lugs O' extend beyond the bottom of the box and the arms N' of the hanger are secured to the lugs O' by cross-bolts P, provided with removable nuts P'.

The hanger N may be formed of a single piece of metal having a vertical opening, N², for the grip-bar and diverging arms N', which are secured to the saddle, as above described. The lower portion of the opening N² is rounded or concave to form a seat for a rounded bearing block or ball, M', on the grip-bar. This affords a universal joint for the grip-bar and permits an easy rocking movement, forming a flexible connection to provide against undue strain. The arrangement also brings the weight under the center of the journals and admits of easy access for the removal of the wheels. In order to limit the vertical movement of the grip-bar and yet permit of its rocking, I attach a short bolt, Q, to the grip-bar at the bearing-block and extend it through the bottom of the hanger. The lower end of the bolt is screw-threaded to receive a nut, R, and between the nut and the bottom of the hanger is interposed a washer, S, having a curved recess in its upper face to conform to the bottom of the hanger. The opening through the bottom of the hanger is slightly enlarged, as shown, so that the bolt may rock with the grip-bar. This arrangement is especially desirable when track-brakes are applied to the grip-bars. It will be observed that these devices for supporting the grip-bars may be applied to any car-truck, as the saddle may be readily supported on the ordinary form of axle-box; but the saddle may be dispensed with if the lugs or ears are cast on the box. The grip-bars may thus be readily removed from the axle-boxes when it is desired to change the wheels.

Having thus described my invention, what I claim as new, and desire to secure by Letters Patent of the United States, is—

1. The combination, substantially as hereinbefore set forth, of the car-body, the axle-box, the supporting-springs, the spring-carriage supporting the springs, means for supporting the spring-carriage from the axle-box, and supports for holding the springs when the spring-carriage is removed.

2. The combination, substantially as hereinbefore set forth, of the car-body, the axle-box, the spring-carriage, means for supporting the spring-carriage from the axle-box, the springs connected with the car-body and resting on the spring-carriage, the post extending through the springs and connected to the carriage, and the supports for holding the springs when the spring-carriage is removed.

3. The combination, substantially as hereinbefore set forth, of the car-body, the axle-box, the spring-carriage supported by the axle-box, the springs connected to the car-body and resting on the spring-carriage, the posts extending through the springs, the guide-blocks,

- the guide-posts extending through the guide-blocks, and means for holding the springs in position on the posts independent of the carriage.
5. The combination, substantially as hereinbefore set forth, of the car-body, the axle-box, the spring-carriage supported by the axle-box, the springs connected with the car-body and resting on the spring-carriage, the guide-blocks, and the guide-posts connected with the car-body and extending through the guide-blocks.
6. The combination, substantially as hereinbefore set forth, of the car-body, the axle-box, the spring-carriage supported thereon, the supporting-springs resting on the carriage, the spring-posts connected to the car-body extending through the springs and through the spring-carriage, the brace-rods having a short section connected to the lower ends of the spring-posts, and devices for securing the section of the brace-rods to the remaining portions of the braces near their junction with the spring-posts and for removing the short section without removing other parts of the braces.
7. The combination, substantially as hereinbefore set forth, of the axle or axle-box, the hanger supported thereby, the grip-bar seated in the hanger, the spring-carriage, and means independent of the grip-bar hanger for supporting the spring-carriage.
8. The combination, substantially as hereinbefore set forth, of the axle or axle-box, the hanger supported thereby, and the grip-bar flexibly supported in the hanger.
9. The combination, substantially as hereinbefore set forth, of the axle-box, the saddle supported thereby, the hanger secured to the saddle, and the grip-bar seated in the hanger.
10. The combination, substantially as hereinbefore set forth, of the axle-box, the hanger supported thereby, the grip-bar seated in the hanger, and means for limiting the movement of the grip-bar in the hanger.
11. The combination, substantially as hereinbefore set forth, of the car-body, the axle-box, the springs, the spring-carriage, the braces, the guide-blocks, and the guide-posts extending through the guide-blocks.

In testimony whereof I have hereunto subscribed my name.
